UNITED STATES PATENT OFFICE.

JOHN P. TARBOX, OF GARDEN CITY, NEW YORK, ASSIGNOR, BY MESNE ASSIGNMENTS, TO CURTISS AEROPLANE AND MOTOR COMPANY, INC., OF GARDEN CITY, NEW YORK, A CORPORATION OF NEW YORK.

COMBINATION LAND, AIR, AND WATER CRAFT.

Application filed September 21, 1922. Serial No. 589,583.

To all whom it may concern:

Be it known, that I, JOHN P. TARBOX, a citizen of the United States, residing at Garden City, in the county of Nassau and 5 State of New York, have invented certain new and useful Improvements in Combination Land, Air, and Water Craft, of which the following is a specification.

My invention relates to aircraft, and 10 more particularly to seaplanes of the "flying boat" type.

A principal object of the invention is the provision of means, preferably under the control of the pilot or other occupant of the 15 craft whereby, if desired, or, should occasion demand, a landing may be made or a "take-off" effected respectively on and from land as well as water.

A further object of the invention is to so 20 organize and relate the parts comprised in the combination gear that an absolute minimum of head resistance is encountered regardless of whether the machine is operated as a land, air, or water craft.

25 A still further object of the invention is to so relate the retractible land lighting gear to the conventional motor supports that in the extended position of the landing gear only a portion of each landing 30 wheel is exposed; the shock absorbing mechanism, as well as the supports for the landing wheels, being effectually housed and adequately streamlined in suitable casings which also enclose the motor supports and the landing wheels when retracted.

35 Other objects, advantages, and improved results will be noted upon a better understanding of the construction and operation 40 of the machine.

In the drawings, wherein like reference characters denote like or corresponding parts:

45 Figure 1 is a front end elevation of an aeroplane constructed in accordance with the present invention, the land operating gear being shown in an extended position.

50 Figure 2 is a side elevation of the machine with the parts positioned as illustrated in Figure 1.

Figure 3 is a detail longitudinal vertical sectional view of one of the streamlined

casings showing the mounting for the wheels of the land operating gear.

Figure 4 is a sectional view taken at 55 right angles to the section in Figure 3.

Figure 5 is a fragmentary sectional view showing the detail construction of the latch mechanism, and

Figure 6 is a section on the line 6—6 of 60 Figure 5.

In the embodiment of the invention selected for illustration a twin motored flying boat of more or less conventional design is shown. Such flying boat comprises 65 a hull or body portion 10 having side fins or excrescences 11 formed on opposite sides thereof in lateral continuation of its hydroplaning bottom surface 12. Preferably the side fins 11 emanate from the extreme bow of the hull or body portion 10 and widen gradually to a point substantially mid-ships where they terminate squarely in line with the transverse step 13 ordinarily to be found in flying boat construction. From the step 13 aft, the bottom 70 of the hull or body portion 10 is inclined upwardly.

Intermediately of its ends the hull or body portion 10 is provided with supporting surfaces 14, said supporting surfaces being preferably superposed and connected by wing struts 15, suitably braced. Between the superposed supporting surfaces 14, and preferably symmetrically at opposite sides of the hull or body portion 10, twin motors 16—16 are disposed. Each motor 16 is supported in its elevated position by means of motor supports 17 bearing at one end directly upon the lower 80 supporting surface. Directly beneath the motor supports 17 the wheels 18 of the land operating gear are disposed. Said wheels 18 are retractible from an extended position below the lowermost point of the 85 hydroplaning bottom surface 12 of the hull 10 to a position above such bottom surface, the wheels in their retracted position being wholly enclosed in suitable streamlined housings or casings 19 extended between the lower supporting surface 14 and the side fins 11. Above the lower supporting 90 surface 14, and in continuation of the casings 19 housings or casings 20 are

provided, the latter casings being of a construction similar to the casings 19 and so related to the motor supports 17 as to completely enclose the same.

5 The wheels 18 of the land operating gear are mounted on axles 21 journaled in bearings (not shown) mounted in the ends of yoke supports 22 slidably mounted within the casings 19. As a guide means for the 10 yoke supports 22 grooves 23 are provided, the grooves 23 being formed on the inside of the casings 19. Within each groove 23 a tongue 24 is disposed, the tongue 24 being slidably vertically within the grooves when 15 the landing wheels 18 are either extended or retracted.

The casings 19 and 20 (see Fig. 4) are vertically aligned. Within the casings 20 the shock absorbing mechanism for the land 20 operating gear is enclosed. Such mechanism comprises a sliding sleeve 24', a fixed sleeve 25, shock absorber elastics 26, and supports or saddles 27 over which the shock absorber elastics 26 are laced. In the extended position of the land operating gear the sleeve 24' is movable relatively to the sleeve 25 and as each sleeve is made as an integral part of the two sets of saddles 27, obviously the displacement of the wheels 18 in landing will cause the shock absorber elastics to yield. The fixed sleeve 25 is flanged at its lower end as at 28 and fastened as at 29 to the lining 30 of the casing 19 into which it extends. In this manner 30 the sleeve 25 is held at all times absolutely rigid. The sleeve 24' for a portion of its length is slidable within the sleeve 25 and at its lower end is closed except for an opening 31. Through the opening 31 a rod 32 extends, said rod at one end being fastened to the yoke support 22 with which it is associated. At its upper end said rod 32 is enlarged as at 33, said enlargement being bifurcated as at 34 to receive in the bifurcation 40 thus formed the latch mechanism by means of which the extension and retraction of the land operating gear is controlled. Such latch mechanism comprises toggle levers 35 pivoted as at 36 and provided at 45 one end with projections 37 which are adapted to enter openings 38 formed in the sliding sleeve 24'. Between the toggle levers 35 a spring 39 is disposed, the function of which is to at all times urge the projections 37 toward said openings 38. At their opposite ends the toggle levers 35 have fastened thereto an operating cord 40 which extends upwardly through the hollow of the sleeve 24' to a pulley 41, and thence laterally inwardly from the pulley 41 to a drum or windlass enclosed in the hull or body 10, preferably in convenient proximity to the pilot's seat. When the projections 37 of the toggle levers 35 are within the openings 38 of the sliding sleeve, rigid connection is ef-

fected between the yoke supports 22 and said sleeve, thereby causing the shock absorber elastics 26 to be stretched in a landing operation. Such rigid connection is maintained at all times when it is desired that the machine be operated as a land machine. To retract the wheels 18 of the land operating gear to positions within the casings 19 the operating cords 40 are pulled inwardly, such pull first withdrawing the projections 37 from the opening 38 by compressing the spring 39, and immediately such projections are withdrawn, bodily withdrawing the wheels 18 inwardly until completely housed with the streamlined casings. Gravity alone is sufficient to extend the wheels when it is desired that they be so extended.

From the foregoing it is obvious that the side fins 11 effectively brace the land operating gear by reason of the direct connection between the side fins and the lower supporting surface. The casings 19 moreover, by reason of their disposition in vertical alignment with the casings 20 position the wheels 18 the desired distance apart and directly beneath the motors 16. The land operating gear, when retracted, by reason of its complete enclosure within the casings 19 and 20 offers no resistance whatsoever to forward travel, and even when extended, an absolute minimum of resistance follows by reason of the fact that only portions of the wheels 18 are exposed.

While I have described my invention in detail in its present preferred embodiment, it will be obvious to those skilled in the art after understanding my invention, that various changes and modifications may be made therein without departing from the spirit or scope thereof. I aim in the appended claims to cover all such modifications and changes.

What I claim is:—

1. A combination land, air, and water craft comprising one or more aeroplane supporting surfaces, a flotation body so disposed in its relation to said supporting surface as to enable operation of the machine on water, wheels likewise so disposed in relation to said supporting surface as to enable operation of the machine on land, mechanism operable to extend and retract the wheels according to whether or not it is desired to operate the machine on land or water, and devices carried by and dependent from the supporting surface on opposite sides of the flotation body within which the wheels are enclosed when retracted.

2. A combination land, air, and water craft comprising one or more aeroplane supporting surfaces, a flotation body so disposed in its relation to said supporting surface as to enable operation of the machine on water wheels likewise so disposed in their relation

- to said supporting surface as to enable operation of the machine on land, mechanism operable to extend and retract the wheels according to whether or not it is desired to 5 operate the machine on land or water, and devices jointly carried by the flotation body and the supporting surface and within which the wheels are enclosed when retracted.
- 10 3. A combination land, air, and water craft, comprising one or more aeroplane supporting surfaces, a flotation body so disposed in its relation to said supporting surface as to enable operation of the machine on water, 15 fin excrescences at opposite sides of the flotation body, wheels likewise so disposed in their relation to said supporting surface as to enable operation of the machine on land, mechanism operable to extend and re- 20 tract the wheels according to whether or not it is desired to operate the machine on land or water, and devices arranged at opposite sides of the flotation body and extending between said supporting surface and the fin 25 excrescences, said devices being so disposed in relation to the wheels aforesaid as to provide an enclosure therefor when said wheels are retracted.
4. A combination land, air, and water craft comprising one or more aeroplane sup- 30 porting surfaces, a flotation body so disposed in its relation to said supporting surface as to enable operation of the machine on water, wheels likewise so disposed in their relation 35 to said supporting surface as to enable operation of the machine on land, a dual power plant arrangement comprising motor supports symmetrically arranged at opposite sides of the flotation body above the lower- 40 most supporting surface, an enclosure ar- ranged vertically beneath each motor sup- port, the enclosures in each instance being extended beneath the supporting surface to provide housings within which the wheels 45 are enclosed when retracted, and mechanism operable to extend and retract said wheels according to whether or not it is desired to operate the machine as a land or water craft.
5. A combination land, air, and water 50 craft comprising one or more aeroplane sup- porting surfaces, a flotation body so disposed in its relation to said supporting surface as to enable operation of the machine on water, wheels likewise so disposed in relation to 55 said supporting surface as to enable opera- tion of the machine on land, a power plant arrangement including separate motor sup- ports symmetrically arranged on opposite sides of the flotation body, mechanism op- 60 erable to extend and retract the wheels ac- cording to whether or not it is desired to operate the machine on land or water, and vertically extending substantially streamlined enclosures disposed beneath said motor 65 supports, the enclosures in each instance be-
- ing extended beneath said supporting sur- face to provide housings within which said wheels are enclosed when retracted.
6. A combination land, air, and water craft comprising one or more aeroplane sup- 70 porting surfaces, a flotation body, a motor support carried by the supporting surface, a wheeled landing gear, mechanism operable to extend and retract the wheels of said landing gear, and a substantially stream- 75 lined housing likewise carried by the sup- porting surface disposed directly beneath the motor support, said housing in its rela- tion to said wheels being such that an enclosure therefor is provided when said 80 wheels are retracted.
7. In a combination land, air, and water craft, an aeroplane supporting surface, a flotation body, a wheel movable from a re- 85 tracted position above the bottom of the flo- 90 tation body to an extended position beneath said bottom, mechanism operable to extend and retract said wheel, shock absorber mechanism for said wheel, and a substan- 95 tially streamlined housing within which the shock absorber mechanism is enclosed and within which the wheel is adapted to be withdrawn when retracted, said housing being laterally spaced out from said flo- 100 tation body.
8. In a combination land, air, and water craft, an aeroplane supporting surface, a flotation body, a wheel movable from a re- 105 tracted position above the bottom of said body to an extended position below said bottom, a power plant arrangement includ- 110 ing a motor support erected directly over said wheel, mechanism operable to extend and retract said wheel, and a substantially streamlined housing carried by the support- 115 ing surface and within which the wheel, when retracted, and the motor support, are enclosed.
9. In a combination land, air, and water craft, an aeroplane supporting surface, a flotation body, a wheel movable from a re- 120 tracted position above the bottom of said body to an extended position below said bottom, shock absorber mechanism for said wheel, a motor support, and a vertically dis- 125 posed housing within which the wheel, when retracted, the shock absorber mechanism, and the motor support, are all completely enclosed.
10. In a combination land, air, and water craft, an aeroplane supporting surface, a flotation body, a wheel movable from a re- 130 tracted position above the bottom of said body to an extended position below said bottom, a motor support, said motor support being positioned directly over said wheel and above the plane of said supporting surface, and a housing carried by and extended above and below said supporting surface, that portion of said housing extended above

- 2
- said supporting surface providing an enclosure for the motor support, and that portion of said housing extended below said supporting surface providing an enclosure 5 for the wheel when retracted.
11. In a combination land, air, and water craft, an aeroplane supporting surface, a flotation body, a wheel movable from a retracted position above the bottom of said 10 body to an extended position below said bottom, shock absorber mechanism for said wheel, a motor support positioned directly above said wheel in a plane above the horizontal plane of said supporting surface, a 15 housing carried by said supporting surface and extended thereabove to provide an enclosure for said motor support and therebeneath to provide an enclosure for said wheel when retracted, said shock absorber 20 mechanism being likewise enclosed within said housing, and mechanism operable to extend and retract said wheel according to whether or not it is desired to operate the machine as a land or water craft.
12. In a combination land, air, and water 25 craft, a flotation body, fin excrescences formed on said body at opposite sides thereof, an aeroplane supporting surface including stub wings extending laterally out from 30 said body on opposite sides thereof, a power plant arrangement including separate motor supports disposed directly over said supporting surface at opposite sides of said body, substantially streamlined housings carried by said supporting surface and extended thereabove and therebeneath, that portion of each housing extended above said supporting surface providing an enclosure for said motor supports, and that portion of 40 each housing extended beneath said supporting surface providing an interconnection between said supporting surface and the fin excrescences, wheels movable within said 45 housings from a retracted position above the bottom of said body to an extended position below said bottom, shock absorber mechanism for each wheel, said shock absorber mechanism being likewise enclosed within said housing, and mechanism operable to extend and retract said wheels. 50
13. In a combination land, air, and water craft, a centrally located flotation body having a hydroplaning bottom surface, a supporting surface a power plant arrangement 55 including separate motor supports mounted upon said supporting surface symmetrically at opposite sides of said body, wheels disposed directly beneath the motor supports, mechanism operable to move the 60 wheels from a retracted position above the hydroplaning bottom surface of the body to an extended position below said bottom surface, and housings positioned directly beneath the motor supports within which 65 said wheels are enclosed when retracted.
- In testimony whereof I hereunto affix my signature.
- JOHN P. TARBOX.
